CLAIM

The ornamental design for a golfclub swing-path and face-angle training-mat, as shown and described.

DESCRIPTION

FIG. 1 is an upper frontal perspective view of an golf club swing path and face-angle training-mat;

FIG. 2 is a top plan view thereof;

FIG. 3 is a rear elevational view thereof;

FIG. 4 is a right side view thereof;

FIG. 5 is a cross section taken on line 5—5 of FIG. 1;

FIG. 6 is a top front perspective view of a second embodiment of the golf club swing path and face angle training mat as disclosed in FIG. 1;

FIG. 7 is a top plan view of FIG. 6;

FIG. 8 is a rear elevational view of FIG. 6;

FIG. 9 is a right side view of FIG. 6; and,

FIG. 10 is a cross section taken on line 5—5 of FIG. 6.

The broken line showing of a golf club and foot prints is for illustrative purposes only and forms no part of the claimed design.
